ATTORNEY'S

UNITED STATES PATENT OFFICE.

FRED A. RICHARDSON AND JOHN J. SCHUSTER, OF DENVER, COLORADO.

HYDROCARBON-OIL BURNER.

1,120,537.

Specification of Letters Patent.

Patented Dec. 8, 1914.

Application filed May 16, 1914. Serial No. 838,921.

To all whom it may concern:

Be it known that we, FRED A. RICHARDSON and JOHN J. SCHUSTER, citizens of the United States, residing at Denver, in the city and county of Denver and State of Colorado, have invented certain new and useful Improvements in Hydrocarbon-Oil Burners, of which the following is a specification.

10 Our invention relates to an improvement in hydro-carbon oil burning devices adapted to burn kerosene or coal oil, or the various grades of hydro-carbon oils.

15 The object is to so construct and arrange the fuel delivery to the pipe that as the fuel is burned, the products of combustion will heat and superheat the oil to generate the gas.

20 The invention relates to still other novel features of construction and combinations of parts which will be hereinafter more fully described and pointed out in the claims.

25 In the accompanying drawings: Figure 1 is a view in elevation of the invention; Fig. 2 is a view in elevation of three forms of burners; Fig. 3 is a top plan view of the invention.

30 The numerals 1 and 2 represent the two burners which are formed from the terminals of the fuel supply pipes and made in the form of coils, the ends of the coils or pipes of the burners 1 and 2 being closed by the caps 4 and 3 respectively.

35 Located beneath the burners is a pan or tray 7 which is preferably made of sheet metal or some metal substance, preferably covered with a layer of fiber asbestos and magnesia.

40 Drip cups 17 and 16 are stationarily mounted on the pan 7 and located beneath the burners 1 and 2. These cups protrude below the lower side of the pan 7, and each has a collar 17' rotatably mounted on its 45 lower protruding portion. These collars are provided with openings or slots 19, which are adapted to register with openings or slots 18 in the cups 16 and 17. Flanges 21 and 22 are connected to the collars 17' at the joining edges of the collars. Pivotally connected to the flanges 21 and 22 is a lever 20 for oscillating the collars for regulating the amount of air to be admitted through the openings 18 and 19 into the 50 cups 16 and 17. The burner pipes extend downwardly, as at 5 and 6, through the

pan 7, and each is provided with a valve 10 and 11 for controlling the flow of the fuel to each of the burners 1 and 2. Pipes 14 connect the pipes 5 and 6 to a coupling 15, 60 to which the fuel supply pipe 32 is connected. A needle valve 30 having an indicator cap 31 thereon is connected to the fuel supply pipe for regulating the fuel discharged to the burners from the reservoir 29. Each of the burners 1 and 2 is provided with openings or notches 24 and 23 respectively, through which the fuel is discharged. Connected to the oil burners at the top thereof along the right-angular portion of 70 the pipes as at 28 and 27 are deflectors 25 and 26.

In the operation of the device, the valves 10 and 11 are opened, permitting some of the fuel to enter the cups 16 and 17, when 75 the fuel will be ignited for the purpose of producing sufficient heat to volatilize the fuel passing down through the burners 1 and 2.

80 After a quantity of fuel has been discharged into the cups 16 and 17, the fuel is cut off. The fuel in the cups is ignited, and after it has burned a short time, the burners will have become heated, so that the fuel in the burners will be volatilized as it issues or passes down through the pipes to the burners. As soon as the pipes of the burners 1 and 2 become heated, the fuel will be again turned on, so that the fuel will issue 85 from the burners.

90 The flame from the burners will then continue to maintain the pipes in a heated condition, so that the fuel will be properly volatilized. A collar 17' will be oscillated by the lever 20 for obtaining the proper 95 size opening in each of the cups to admit sufficient air to produce combustion.

We claim:

1. In a hydro-carbon oil burning device, the combination with a coil burner having 100 an outlet at the lower end of the coil, of a cup located with its bottom beneath said outlet in which the fuel may drip, said cup provided with openings beneath the fuel outlet, and means for controlling the admission of air through said openings.

2. In a hydro-carbon oil burning device, the combination with a coil burner pipe having an outlet at the lower end of the coil, of a cup located with its bottom beneath said 110 outlet, said cup having openings therein beneath the fuel outlet, a collar mounted on

said cup provided with openings, adapted to register with the openings in the cup through which air is admitted to the cup, and beneath the burner outlet, means for regulating the admission of air through the openings, and a deflector carried by the burner pipe at the upper end of the coil for deflecting the flame in the direction desired.

In testimony whereof, we have hereunto affixed our signatures in the presence of wit-

nesses, in the city and county of Denver and State of Colorado, this 5th day of May, A. D. 1914.

FRED A. RICHARDSON. [L. S.]
JOHN J. SCHUSTER. [L. S.]
